ATTORNEY.

UNITED STATES PATENT OFFICE.

GEORGE W. KNAPP, OF BALTIMORE, MARYLAND.

DESIGN FOR A BAKING-PAN.

SPECIFICATION forming part of Design No. 27,486, dated August 3, 1897.

Application filed April 14, 1897. Serial No. 632,181. Term of patent 7 years.

To all whom it may concern:

Be it known that I, GEORGE W. KNAPP, a citizen of the United States, residing at Baltimore, in the State of Maryland, have invented 5 and produced a new and original Design for a Baking-Pan, of which the following is a specification.

Figure 1 is a side view of a baking-pan, showing my new design. Fig. 2 is a top view of 10 same. Fig. 3 is an end view of same. Fig. 4 is a cross-section of the upper half of the baking-pan.

As shown, the leading feature of the design 15 for a baking-pan consists of a single cylindric vessel with half-spherical ends A and a central longitudinal flange B, extending continuously or all around the exterior sides and half-spherical ends, the said flange projecting ra-

dially and uniformly all around. The flange is double, and has at intervals short upward 20 bends or downward bends or kinks c. The top of this single pan has the same appearance as the bottom. The surface of the pan is plain or smooth.

Having described my invention, what I 25 claim as new, and desire to secure by Letters Patent, is—

The design for a baking-pan, as herein shown and described.

In testimony whereof I affix my signature 30 in the presence of two witnesses.

GEORGE W. KNAPP.
